UNITED STATES PATENT OFFICE

FRANK J. MATCHETTE, OF MILWAUKEE, WISCONSIN, ASSIGNOR, BY MESNE ASSIGNMENTS, TO RICHMOND RADIATOR COMPANY, OF NEW YORK, N. Y., A CORPORATION OF DELAWARE.

DUST-COLLECTOR.

1,157,242.

Specification of Letters Patent. Patented Oct. 19, 1915.

Application filed September 24, 1904. Serial No. 225,761.

To all whom it may concern:

Be it known that I, FRANK J. MATCHETTE, a citizen of the United States, residing at Milwaukee, in the county of Milwaukee and State of Wisconsin, have invented certain new and useful Improvements in Dust-Collectors, of which the following is a specification, reference being had to the accompanying drawing, forming a part thereof.

10 This invention relates to that class of pneumatic cleaning apparatus in which dust and dirt are taken up and removed from carpets, furniture, etc., with a draft or current of air produced by a vacuum or partial 15 vacuum.

Its main objects are to separate the dust and dirt from the air away from and independently of the moving suction head by which they are collected or taken up, thus 20 admitting of the employment of a light, simple and easily operated device for gathering and removing the dust and dirt from an extended area or from different points without carrying the collected dust and dirt 25 about during the operation, and generally to simplify and improve the construction and operation of apparatus of this class.

It consists in certain novel features of construction and in the peculiar arrangement and combinations of parts hereinafter 30 particularly described and pointed out in the claim.

In the accompanying drawing like characters designate the same parts in the several figures.

Figure 1 is a side elevation of apparatus embodying the invention; Fig. 2 is a vertical section on the line 2 2, Fig. 3, of the dust separator; and Fig. 3 is a horizontal 40 section of the same on the line 3 3, Fig. 2.

The apparatus comprises a portable device A, which may be called a separator, for separating dust and dirt from the air with which it is taken up and collected, a portable suction head B, having a flexible pipe connection C with the separator, and an injector D, having a compressed air supply connection E and constructed and arranged 45 to exhaust air from the suction head B and to force it with dust and dirt taken up and carried therewith, into the separator.

The separator A comprises a basin or receptacle f for catching and holding dust and dirt as they are separated from the air 50 and with which they are collected, a pipe g

leading through one side of said basin and extending upwardly therefrom, a muffler h into which said pipe opens at its upper end, a bell-shaped deflector i surrounding said muffler and a strainer j inclosing said deflector with said basin. The basin f is provided with wheels k and a caster l and with a handle m for moving the separator from place to place. The bottom of the basin is provided with a slide n for removing the 60 dust therefrom and the sides of the basin are preferably inclined downwardly and inwardly toward said slide.

The muffler h consists of concentric perforated spheres or of inner and outer perforated shells, the pipe g being attached at its upper end to and communicating with the interior of the inner shell, and the outer shell having a depending rim surrounding said pipe at a distance therefrom. The deflector i is attached to and supported by the upper part of the muffler. The strainer j, which may be conveniently made of cloth, is detachably fastened by a thumb screw o to the upper end of a rod extending upwardly from the top of the muffler, and is thus suspended over the basin f and deflector i. It is secured to the rim of the basin f by an elastic band s, or other suitable means.

The injector D consists of a Y-shaped casing, the stem of which is coupled to the lower end of the pipe g, and of a nozzle p threaded in one branch of said casing and projecting into the stem thereof toward its 90 connection with the pipe g.

The compressed air pipe E may be coupled either with the outer end of the nozzle p or with an elbow connection q, swiveled in one side of the branch of the injector casing in which the nozzle is inserted, the casing being formed inside with an elongated annular recess and the nozzle with a series of lateral openings for the passage of air into it from the side connection. The outer end of the nozzle p is squared or otherwise formed to receive a wrench for turning and adjusting it longitudinally in the casing. When the compressed air pipe or hose E is coupled with the elbow connection q, the outer end of the nozzle p is closed with a cap, as shown in Fig. 1, and in case said pipe or hose is connected with the outer end of the nozzle, the lateral connection will be closed or omitted. The suction hose or pipe 100

100

95

105

110

C is connected with the outer branch of the injector casing, as shown in Fig. 1.

The suction head B is formed in the base or under side with a slot or aperture and is provided with a tubular handle *r*, to which the hose or pipe C is attached. This part of the apparatus may be varied in size and form according to the class of work it is designed to perform. The form shown in Fig. 1 is specially designed for cleaning carpets, rugs and the like. Suction heads of different forms and sizes may be provided and used in connection with the same separator for operation on different articles and for different classes of work.

The apparatus as shown, operates as follows: The separator A being placed at some convenient point where it will be out of the way, as in the corner of a room to be cleaned or in an adjoining room, and the pipe or hose E connected with an air compressor or source of compressed air, air is admitted to the nozzle *p* and issuing therefrom in a strong jet, exhausts the air from the suction head B through its tubular handle and the hose C, and forces it through the pipe *g* into the separator. The suction head B is moved by the operator over the surface of the carpet or article to be cleaned, and the strong air draft induced by the injector through the slot or aperture in the base of said head takes up dust and dirt and discharges them through the pipe *g* into the muffler *h* within and underneath the bell-shaped deflector *i*. The muffler breaks up and dissipates the strong air blast issuing from the upper end of the pipe *g*, preventing or reducing the noise which its unobstructed discharge would otherwise produce. The rim on the under side of the outer shell of the muffler and the deflector *i*, direct the dust and dirt downwardly toward the basin

f, in which they are caught and held while the air escapes through the strainer *j*, removing therefrom fine dust and particles of dirt which ultimately settle into said basin. The nozzle *p* may be adjusted by screwing it into or out of the injector casing to secure the most effective operation of the apparatus and obtain the best results under varying conditions of air pressure, etc.

The hose C is made of sufficient length to admit of covering the desired area or field of operation with the suction head B without moving the separator A, the location of which however, may be easily changed whenever it is desired.

Various changes in the details of construction and arrangement of parts may be made within the principle and intended scope of the invention.

I claim:

In a pneumatic apparatus for conveying and separating dust and dirt from air, the combination of a dust separator comprising a catch basin having an opening in the bottom provided with a closure, a bell-shaped deflector supported above said basin, a strainer open to the atmosphere and enveloping said deflector together with said basin, a pipe leading into the separator and opening into said deflector, a dust laden air conveying pipe connected with the pipe leading to said deflector, and means to exhaust air from said pipe and force it with entrained dust and dirt into the deflector in said separator, substantially as described.

In witness whereof I hereto affix my signature in presence of two witnesses.

FRANK J. MATCHETTE.
